(57) **CLAIM**

The ornamental design for a packaging for a drug blister-pack for clinical trial, as shown and described.

DESCRIPTION

FIG. 1 is a top plan view of packaging for a drug blister-pack for clinical trial, showing our new design;

FIG. 2 is bottom plan view thereof;

FIG. 3 is a front elevational view thereof;

FIG. 4 is a rear elevational view thereof;

FIG. 5 is a side elevational view thereof from the left of FIG. 3, the side opposite that shown in FIG. 5 being the mirror image thereof; and,

FIG. 6 is a perspective view thereof in an open position.
